UNITED STATES PATENT OFFICE.

ARVEL A. BOSTON, OF NEW MARTINSVILLE, WEST VIRGINIA.

BATTERY FILLER.

1,423,393.

Specification of Letters Patent.

Patented July 18, 1922.

Application filed September 8, 1919. Serial No. 322,255.

To all whom it may concern:

Be it known that I, ARVEL A. BOSTON, a citizen of the United States, residing at New Martinsville, in the county of Wetzel and 5 State of West Virginia, have invented new and useful Improvements in Battery Fillers, of which the following is a specification.

This invention relates to devices primarily intended for filling storage batteries, and 10 has for an object the provision of a device which may be secured to a bottle, or other container by means of which distilled water may be poured into the battery cells without coming in contact with metal, or other 15 injurious substances.

Another object of the invention is the provision of a device of this character, which will normally maintain the bottle in closed condition for the protection of its contents, but which will be automatically opened 20 when used for filling the battery.

A further object is the provision of a device of this character, which is simple in construction and operation and which may 25 be readily connected to bottles or containers of various kinds.

Other objects and advantages of the invention will appear as the following description is read in connection with the accompanying drawings.

In the drawings:

Figure 1 is a longitudinal sectional view of the invention applied to a bottle and shown in closed position.

Figure 2 is a similar view with the device in position for use.

Figure 3 is a top plan view of the device per se.

Figure 4 is a section on the line 4—4 of 40 Figure 1.

Referring to the drawings in detail, like characters of reference denote corresponding parts throughout the several views.

The device may be constructed of any 45 suitable material and comprises a tubular member 10, one end of which is threaded, as shown at 11, for engagement with a suitable stopper 12, the latter being designed to be placed within the mouth of a bottle 50 13. The member 10 is surrounded by an annular flange 14, for the purpose of forming a stop, which is adapted to engage the stopper 12 to limit its insertion within the said stopper.

55 Slidably mounted upon the tubular member 10, is a sleeve 15, and positioned between

this sleeve and the flange 14 and surrounding the member 10, is a coiled spring 16, the purpose of which is to force the sleeve in a direction away from the bottle.

60

The inner end of the tubular member 10 is formed with a curved seat 17, for the reception of a preferably semi-spherical valve 18, the latter being carried by a stem 19, which passes through and beyond the 65 end of the tubular member 10. Located adjacent to but spaced from the outer end of the stem 19, is an opening 20, which receives a transversely disposed pin 21. This pin operates in oppositely located longitudinal 70 slot 22, formed in the tubular member 10 and extends beyond the said member, and has its ends normally positioned within grooves 23, located upon diametrically opposite sides of the interior of the sleeve 15. 75 The tubular member 10 is further provided with openings 24, which are spaced from the outer end of the said member.

In the use of the invention, the bottle, which may contain distilled water, has the 80 invention secured thereto. By inverting the bottle, the outer end of the tubular member 10 may be inserted within the filling opening of the battery cell, so that the outer end of the stem 19 will contact with the plates, 85 sufficient pressure being exerted to press the stem slightly inward. This unseats the valve 18 and permits the water to pass outward through the openings 24 into the battery cell. This prevents the water from 90 coming in contact with any metallic or injurious substances, and further prevents spilling water over the top of the battery. When sufficient water has been placed within the cell, the device may be removed from 95 the battery, whereupon the spring will immediately cause the valve to be seated, so as to prevent further discharge of the contents of the bottle.

By locating the openings 24 from the end 100 of tubular member 10, a semi-automatic action can be obtained by filling the battery to exactly the proper height.

The invention is susceptible of various changes in its form, proportions and minor 105 details of construction and the right is herein reserved to make such changes as properly fall within the scope of the appended claim.

Having described the invention, what is 110 claimed is:

In combination with a container having

a discharge mouth and a stopper therefor having a threaded aperture, of a casing having escape ports in its outer end its inner end threaded and provided with an annular flange surrounding said casing adjacent the threaded portion, a curved seat formed within the threaded end, a semi-spherical valve normally engaging the seat, a stem oblong shape in cross section carried by said valve and passing through and beyond the outer end of said casing, a transversely disposed pin secured through the stem adjacent its outer end and adapted to

reciprocate within oppositely disposed longitudinal slots formed in the outer end of the 15 casing, a sleeve surrounding the casing and normally positioned over the escape ports, said sleeve being provided with grooves disposed upon diametrically opposite sides of its interior, and is adapted to receive the 20 ends of the pin, and a coil spring engaging the sleeve and the annular flange for the purpose specified.

In testimony whereof I affix my signature.

ARVEL A. BOSTON.
